UNITED STATES PATENT OFFICE.

CHARLES LIECK, OF GREAT NECK, NEW YORK, ASSIGNOR OF ONE-HALF TO EDWARD J. BURKE, OF GREAT NECK, NEW YORK.

VALVE-LIFTER.

1,264,098.

Specification of Letters Patent. Patented Apr. 23, 1918.

Application filed August 20, 1917. Serial No. 187,286.

To all whom it may concern:

Be it known that I, CHARLES LIECK, a subject of the Emperor of Germany, but having declared my intention to become a citizen of the United States, and a resident of Great Neck, in the county of Nassau and State of New York, have invented a new and Improved Valve-Lifter, of which the following is a full, clear, and exact description.

10 This invention relates to tools or implements for internal combustion engines or the like and has particular reference to a tool or implement for manipulating valve springs of such machines.

15 Among the objects of the invention is to provide a hand operated tool or implement peculiarly designed for manipulating valve springs that may be located in such a position as to be practically inaccessible by ordinary means.

20 Another object of the invention is to provide a valve lifter or valve spring lifter embodying a substantially bell crank lever having a rocker fulcrum, the fulcrum member 25 and one arm of the lever being adapted for peculiar action in the nature of a toggle whereby a maximum throw of the lifting end of the lever may be effected with a minimum throw of the longer or handle end of 30 the lever, yet with a moderate expenditure of power.

25 A still further object is to provide a valve spring lifter adapted for coöperation with what is known as a V type engine in which 35 the manipulation of the valve must be effected within the V or between the two series of cylinders beneath the manifolds, the implement being provided with a member for co-operation with one of the manifolds to hold 40 or lock the device with the spring elevated, while the manipulation of the valve is being performed.

45 With the foregoing and other objects in view the invention consists in the arrangement and combination of parts hereinafter described and claimed, and while the invention is not restricted to the exact details of construction disclosed or suggested herein, except as required by the scope of the 50 appended claims, still for the purpose of illustrating a practical embodiment thereof reference is had to the accompanying drawings, in which like reference characters designate

the same parts in the several views, and in which

55 Figure 1 is a vertical transverse section of a fragment of a high powered internal combustion engine of the character referred to showing in full lines the position of my improved lifter just after it is introduced, and 60 indicating in dotted lines the position of the lifter when the spring is lifted and held in elevated position by the lock operating with the manifold on the opposite side of the vertical longitudinal plane of the engine. 65

Fig. 2 is a vertical central sectional view of the improvement on the line 2—2 of Fig. 3.

Fig. 3 is a front elevation of the implement as it will be seen looking toward the 70 left in Fig. 2; and

Fig. 4 is a transverse section on the line 4—4 of Fig. 2.

Referring now more particularly to Fig. 1 I show a standard or well known type of 75 high powered engine of what is known as the V type and comprising a body 10 in which are mounted cam operated plungers 11 coöperating with the stems 12 of valves 13 associated with a series of engine cylinders 80 14 on opposite sides of the vertical longitudinal plane midway between the series or rows of plungers 11. The axes of the cylinders in engines of this type diverge from each other on opposite sides of said longitudinal vertical plane at an angle of approximately 60 degrees with the valve casings 15 arranged between the cylinders of the several series and with the manifolds 16 leading to the valve chambers relatively close together between the opposite series of valve chambers. I also indicate at 17 one of the removable cylinder heads in which are located the valves 13. It will be noted also that the engine body is provided along its 95 top with parallel grooves or channels 18 which extend along the series of plungers. I make the foregoing specific reference to the structure of the engine, which *per se* is not my invention, only for the purpose of 100 laying a proper basis for the description of the operation of my improvement.

In accordance with the usual practice in engines of this type, each valve stem 12 is provided with a key 19 projecting through 105 the lower end thereof and within or below

- the washer 20. This washer serves as a support for the lower end of the strong coil spring 21 whose upper end is seated around a boss 22 through which the valve stem reciprocates under the action of the plunger 11. In order to remove the valve 13 for regrinding of the valve seat or other purpose it is necessary to forcibly compress the spring 21, lifting the washer 20 for this purpose far enough along the stem to permit the key 19 to slip out after which the valve may easily be withdrawn, assuming that the head 17 is removed. Because of the fact that the spring is very stiff and the key devices are accessible with difficulty, due to the type of the engine indicated, it is usually a very laborious task and one requiring a considerable expenditure of time to remove and replace all of the valves of one of these high powered engines.
- I now refer specifically to my improved tool or implement the same comprising a bell crank lever 23 having a longer handle or power arm 24 and a shorter or load arm 25 having a fork 26 lying approximately in a plane perpendicular to the handle 24. The ends of the fork are provided with horizontal aligned holes in which is pivoted a cradle 27. The cradle comprises a substantially flat arc shaped base 28 and an upstanding flange 29 lying adjacent to the crotch portion of the fork. The base 28 as indicated has an open center 30 adapted to embrace the key 19 while the cradle slips beneath the washer 20, the flange 29 fitting directly around the periphery of the washer. See Fig. 1. As indicated in dotted lines in Fig. 4 the axis of the valve stem 12 lies between the axis of the pivots 31 and the fork so that when the cradle is inserted into operative position, as shown in full lines in Fig. 1, there is no probability that the cradle will tilt around the axis of the pivots 31 in an outward or downward direction so as to occasion the slipping of the cradle from the washer in the manipulation of the lever. Rather the tendency is for the cradle to crowd the more firmly into engaging position upon the washer.
- At 32 I indicate a rocking fulcrum member, the same being bifurcated at its upper end straddling the pivot portion 33 of the lever and pivoted thereto permanently by means of a pin 34 keyed or otherwise fitted transversely through the lever and upper end of the fulcrum member. The lower end or point 35 of the fulcrum member is adapted to rest in the groove 18 remote from the valve being manipulated and while a sufficient amount of tilting or rocking of the fulcrum member toward and from the axis of the valve is permitted by the point 35 acting in said groove, there is no possibility of said point slipping laterally from the seat or groove 18 in practice. The arm

25 of the lever though much shorter than the handle arm 24 is yet preferably slightly longer than the fulcrum member 32. The lever and fulcrum parts are so proportioned and designed that when the implement is introduced into operative position, the full line position of Fig. 1, preliminary to the lifting of the spring, the arm 25 and the fulcrum member lie approximately at a right angle to each other, but with the line 70 joining the point 35 and axis of the pivot 34 lying beyond the handle 24 or between said handle and the axis of the valve being manipulated. The handle 24, however, occupies a position at this time close to the manifold pertaining to the valve under consideration and approximately parallel to valve stem. When the operator grasps the handle and draws it rearwardly or toward the opposite manifold there results a compound 80 movement due to the lengthening of the toggle or articulation of the bell crank and fulcrum member at the pivot 34 and the rocking of the fulcrum member around its point 35. In other words the force applied 85 to the lever by the operator's hand is so resolved that the fulcrum member 32 is rocked forward toward the valve stem while the cradle or fork end of the lever is elevated due to both the bell crank action of the lever 90 and lengthening of the toggle. Hence the handle end of the lever and the fulcrum member may be said to move in opposite directions. Since, however, the cradle maintains its position on the washer and is elevated, the movement of the cradle must be precisely the same as that of the washer resulting from such combined movement of the implement. In other words the washer is lifted so as to move directly along the 95 valve stem in a straight line and with the base 28 of the cradle always remaining parallel to itself, due to the tilting of the cradle around its pivots 31. This operation of the lever is an easy and natural one from the 100 viewpoint of the operator, requiring no special care on his part to maintain the cradle in embracing position upon the washer. The spring even though very stiff is thus easily 105 compressed to an extent giving ample clearance for the key irrespective of the position of the plunger 11. In other words the operator may easily and quickly remove and replace all twenty-four of the valves of a twelve cylinder V type engine without manipulating the cam shaft or any other rotary part of the engine as is so commonly 110 required in these operations.

At 36 I show a hook of any suitable character pivoted at 37 upon the handle end 24 115 of the bell crank lever. This hook is so placed and designed as to engage easily over the manifold 16 toward which the handle is moved while lifting the valve spring and in this position, as shown in dotted lines in 120

130

Fig. 1, the hook is adapted to hold the lever while the valve is being manipulated and the key is being replaced.

The principal parts of this implement may 5 be cheaply and effectively formed by stamping from sheet metal and bending into the desired shape. The rocker member may be of sheet metal or as indicated may be either a casting or a drop forging, hence 10 the device is unusually simple and cheap to manufacture and is not only easy but thoroughly reliable of manipulation and practically indestructible with ordinary care.

15 I claim:

1. The herein described valve spring lifter for V type engines the same comprising a bell crank lever having a forked load end, a rocking fulcrum member pivotally 20 connected to the lever, and a cradle pivoted in the forked end of the lever, said cradle comprising an arc shaped member adapted to straddle the valve stem below the spring, the center of the arc thereof adapted to coincide 25 with the axis of the valve stem lying between the axis of the cradle pivots and the fork to insure the cradle from slipping from the spring when power is applied to the lever.
2. In a valve spring lifter for engines of the type indicated, the combination of a member to embrace the valve spring washer, a bell crank lever in the load end of which said member is pivoted, and a fulcrum member for the lever movable auto- 30
- 35

matically toward the axis of the valve stem while power is applied to the lever away from said axis to compress the spring.

3. The herein described lifter for a valve spring compressible in a straight line along 40 the axis of the valve stem, the same comprising a flat member adapted to engage beneath the end of the spring around the axis of the same, a bell crank lever carrying said flat member at its load end, the 45 handle end of the lever being adapted to extend approximately parallel to the stem axis when said member is applied to the spring, and an automatically movable fulcrum member for the lever, said fulcrum being 50 movable toward the axis of the stem when power is applied to the handle end of the lever away from said axis to compress the spring.

4. The herein described valve lifter comprising 55 a bell crank lever of the first class having a shorter arm and a longer arm arranged approximately at right angles to each other, the shorter arm having a forked end, the plane of the fork being approximately perpendicular to the axis of the longer arm, a spring engaging member pivoted in the plane of the fork, and a fulcrum member for the bell crank lever pivotally connected thereto adjacent to the angle thereof. 60

CHARLES LIECK.

In the presence of—

AUSTIN HICKS,
GEO. P. NINESLING.
